CLAIM

The ornamental design for a lock out box, as shown and described.

DESCRIPTION

FIG. 1 is a top, front, and left side perspective view of a lock out box showing our new design in an open configuration; FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a bottom plan view thereof;

FIG. 8 is an enlarged portion view labeled as "FIG. 8," taken from FIG. 1; and,

FIG. 9 is another top, front, and left side perspective view thereof.

The dashed-dot lines in FIGS. 1 and 8 illustrate the boundary line of the enlarged portion view of FIG. 8. The broken lines in the reproductions in FIGS. 2, 4, 7 and 9 illustrate portions of the lock out box that form no part of the claimed design.
